HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

HATCH CONSTRUCTION

Application filed September 4, 1928. Serial No. 303,706.

This invention relates to submarine boats, and more particularly to an extensible hatch construction for such boats.

The use of the diving bell for submarine work is well known. It is extremely difficult, however, to use a diving bell for rescuing men entrapped in an injured submarine boat, or in a submarine boat which for any other reason is submerged at an appreciable depth 10 and is unable to rise to the surface. This difficulty in using the diving bell to rescue men from a submarine boat is due largely to the fact that submarine boats of accepted design do not have any projections which would 15 extend into the bell so as to exclude the water from the submarine upon opening of the hatch covers.

There are certain inherent advantages in the use of a diving bell, particularly when 20 working at great depth, such as its ability to withstand high pressures and its relatively wide open mouth which facilitates seating of the bell upon the superstructure of a submarine above and about an escape hatch. It is 25 the primary object of my invention to provide a hatch construction for submarines having an extension tube which can be extended so as to project an appreciable distance upwardly beyond the superstructure 30 into a diving bell seated upon such superstructure. In this manner the water is excluded from the hatch upon opening thereof and the men entrapped in the submarine can 35 pass therefrom through the hatch structure directly into the diving bell. A further object is to provide an extensible hatch structure of the character stated which can be readily applied to submarine boats of present 40 design and which is of relatively simple and inexpensive construction. Further objects and advantages of my invention will appear from the detailed description.

In the drawings:—

Fig. 1 is a sectional view through a hatch construction in accordance with my invention, as applied, showing the extension tube thereof projected and the manner in which this tube cooperates with a diving bell seating upon the superstructure;

Fig. 2 is a section taken substantially on line 2—2 of Fig. 1;

Fig. 3 is a section taken substantially on line 3—3 of Fig. 1; and

Fig. 4 is a fragmentary detail sectional view 55 illustrating the means for effecting a water-tight closure between the trunk tube and the extension tube.

I have illustrated my invention as applied to a submarine boat of known type having a hull 1 and a superstructure 2. A hatch trunk 3 extends through the hull 1 and is secured thereto in a known manner. This trunk is provided, at its inner end and at diametrically opposite points thereof, with two offsets 60 or pockets 4. Drums 5 are disposed within these pockets, these drums being secured on shafts 6 supported for rotation in a suitable manner, these shafts passing out of the hatch trunk 3 through suitable stuffing boxes 7. 70 The outer ends of the shafts have bevel gears 8 secured thereon and each shaft passes through a bearing structure 9, adjacent gear 8, this structure being carried by one arm of a bracket 10 suitably secured to hatch trunk 75 3. Each of the brackets 10 is provided with a second arm carrying a bearing structure 11. An operating shaft 12 is rotatably mounted through the bearing structure 11 and is provided with bevel gears 13 secured thereon and meshing with the gears 8. A hand wheel 14 is secured upon one end of shaft 12. By turning shaft 12 the drums can be 80 turned in desired directions.

A trunk tube 15 has its lower end secured 85 in the lower end of trunk 3 in a suitable manner. This tube terminates short of the upper end of the trunk and receives, in telescoping relation, an extension tube 16. This tube is disposed inside of tube 15 in concentric relation thereto and, when in extended position, fits snugly through an end ring 17 90 at the upper or outer end of trunk 3. This ring is surrounded by a collar 18 and the ring and the collar are secured in the upper end 95 of trunk 3 in a suitable manner to effect a water and pressure tight closure therewith, as by being accurately dressed and shrunk into the end of the trunk. Ring 17 is provided with an upwardly extending lip or 100

bead 19 which coats with a packing member or gasket of a cover 20 for effecting a fluid tight closure of the upper end of the trunk. This cover is hinged upon the trunk and is moved into open or closed position from within hull 1 by means of an operating rod 21 having pin and slot connection with an arm extending from the cover. This rod and the manner of mounting and operating it is disclosed in detail in my co-pending application for escape hatch for submarines, Serial No. 275,730, filed May 7, 1928, and need not be illustrated nor described herein in detail. When the cover 20 is closed, it is secured by suitable dogs or equivalent means in a known manner. A cover 22 is hingedly mounted upon the trunk 3 at the lower end thereof and this cover is also secured closed by dogs or other suitable means for effecting a fluid tight closure between the cover 22 and the inner end of the trunk, as is well understood in the art.

Two guide pulleys are suitably supported by brackets 24, or in any other suitable manner, at the upper end of trunk 3 and in alignment with the drums 5. Wires 24', which may be in the nature of light and readily flexible steel cables, pass over the pulleys 23 and are secured to the drums 5, at one end, so as to be windable onto and off of the same. The other ends of these wires are suitably secured to the extension tube 16 adjacent the lower or inner end thereof. When the wires or cables 24' are wound upon the drums 5, the tube 16 is extended to project outwardly of the hull beyond the hatch trunk 3. By unwinding the cables from the drums the tube 16 is permitted to move downwardly inside of the tube 15 into its full lowered or retracted position. In this position the tube 16 is disposed within the trunk 3, this tube being of slightly less length than the trunk. With the tube 16 in retracted position, the closure members or covers 20 and 22 for the ends of the trunk can be closed and secured in closed position.

Outward movement of tube 16 is limited by a stop member 25 secured to the inner face of tube 15 and extending inwardly of this tube radially thereof, this member having its upper portion turned inwardly and downwardly to form a channel element 26. The inner flange of element 26 is disposed to fit into a channel element 27 formed at the lower end of tube 16 integrally therewith.

A packing gasket 28 is mounted in element 27 and cooperates with the inner flange of element 26 to effect a water-tight closure between the two tubes when the tube 16 is in full extended position. In this manner, the means for limiting outward movement of tube 16 also serves to effect a closure between the two tubes. This closure need not be capable of resisting high pressures since the pressure within the hull 1 is built up so as to be equal

to the external water pressure before opening of the hatch covers and movement of tube 16 into extended position.

I have illustrated my invention as used in connection with a diving bell B of known type provided with a circular platform b, air under pressure being supplied to this bell through a hose h in a known manner. An eye e is secured to the bell and receives a cable c by means of which the bell is raised and lowered. In using my improved hatch construction, the bell B is first lowered into position and seated upon the superstructure 2 over and about the hatch trunk 3. After the bell has been properly positioned the occupants of the submarine boat are advised of this fact in any suitable manner and water is admitted to the trunk 3. For this purpose any suitable valve arrangement may be employed, though I prefer to employ two valves, one operable exteriorly of the hull by a diver for admitting the water to the hatch trunk and the other operable from within the hull.

It is thus possible, by using the two valves, for the diver to admit water to the hatch trunk to neutralize the pressure on the outer cover 20 in the event that the occupants of the submarine are, for any reason, unable to do so. Under ordinary conditions, however, the occupants of the submarine would admit water to the trunk 3 to neutralize the pressure exerted by the water on the exterior surface of cover 20. After this is done, cover 20 is moved into open position, cover 22 remaining closed and the tube 16 is raised into its fully extended position. In this position the tube 16 projects above the water line in bell B, as illustrated in Fig. 1. After the tube 16 has been fully extended, the lower cover 22 is released and opened, discharging the water in the trunk and the tube 16 up to the level of the water line in the bell B, into the hull 1. The men then escape from the submarine through the trunk tube 15 and extension tube 16, by means of suitable ladders 29 and 30, and are assisted by the men in the bell B onto the platform b thereof, it being understood that several men are lowered with the bell initially to properly position the same and assist in the rescue of the men entrapped in the submarine. After all of the men from the submarine boat have entered the bell B this bell is slowly raised to the surface and the air pressure in the bell is gradually reduced, in a known manner.

What I claim is:—

1. In combination in a submarine boat, a hatch trunk opening through the hull, a trunk tube fixed within the trunk, an extension tube telescoping the trunk tube and movable outwardly thereof to project beyond the hull, removable closures for the ends of the trunk, said extension tube being disposed within the trunk when in retracted position, means for opening the outer closure from

within the hull, means for extending said extension tube from within the hull, and means for limiting outward movement of the extension tube and for effecting a water-tight closure between the tubes.

5 2. In combination in a submarine boat, a hatch trunk opening through the hull, a trunk tube fixed within the trunk, an extension tube telescoping the trunk tube and movable outwardly thereof to project beyond the hull, removable closures for the ends of the trunk, said extension tube being disposed within the trunk when in retracted position, and means for limiting outward movement 10 of the extension tube and for effecting a water tight closure between the tubes.

15 3. In combination in a submarine boat, a hatch trunk opening through the hull, a trunk tube within the trunk, an extension tube telescoping the trunk tube and fitting into the latter, the extension tube having an outwardly directed channel element at its inner end, a stop member projecting inwardly of the trunk tube radially thereof and extending toward the inner end of the trunk tube for engagement into said channel element, packing means cooperating with the channel and stop members for effecting a water-tight closure therebetween when the extension tube is in 25 its outermost position, said extension tube being disposed within the trunk when retracted, and removable closures for the ends of the trunk.

30 4. In combination in a submarine boat, an access hatch structure opening through the hull, a tube telescoping the hatch structure and movable outwardly beyond the outer end thereof, means for limiting outward movement of the tube relative to the hatch structure and for effecting a closure between the tube and the hatch structure when the tube is extended, the tube being disposed within the hatch structure when in retracted position, said tube being unobstructed and open at its 35 ends and the hatch structure being open at its ends, whereby ingress to and egress from the interior of the hull is had through the tube, and removable covers for the ends of the hatch structure.

45 5. In combination in a submarine boat, an access hatch structure opening through the hull into a compartment thereof and having its lower end adjacent the top of the compartment, a tube telescoping the hatch structure and movable outwardly beyond the outer end thereof, means for limiting outward movement of the tube relative to the hatch structure and for effecting a closure between the tube and the hatch structure when the tube is 50 extended, the tube being disposed within the hatch structure when in retracted position, said tube being unobstructed and open at its ends and the hatch structure being open at its ends, whereby ingress to and egress from 55 the interior of the hull is had through the

tube, and removable covers for the ends of the hatch structure.

6. In combination in a submarine boat, an access hatch structure opening through the hull, a tube telescoping the hatch structure and movable outwardly beyond the outer end thereof, means for limiting outward movement of the tube relative to the hatch structure and for effecting a closure between the tube and the hatch structure when the tube is extended, the tube being disposed within the hatch structure when in retracted position, said tube being unobstructed and open at its ends and the hatch structure being open at its ends, whereby ingress to and egress from the interior of the hull is had through the tube, a removable cover for the outer end of the hatch structure and opening outboard and a removable cover for the inner end of the hatch structure and opening inboard.

In witness whereof, I hereunto subscribe my name this 8th day of August, 1928.

HUGO E. GRIESHABER.
